US00D941127S

(12) United States Design Patent (10) Patent No.: US D941,127 S
(45) Date of Patent: * Jan. 18, 2022

(54) HOOKING DEVICE

(71) Applicant: Charles Weiss Sutliff, II, Kila, MT (US)

(72) Inventor: Charles Weiss Sutliff, II, Kila, MT (US)

() Term: 15 Years

(21) Appl. No.: 29/647,382

(22) Filed: May 11, 2018

(51) LOC (13) Cl. 08-05

(52) U.S. Cl.

USPC D8/370

(58) Field of Classification Search

USPC D8/370, 372, 382, 383, 44

CPC F16B 2/248

See application file for complete search history.

(57) CLAIM

The ornamental design for hooking device, as shown and described.

DESCRIPTION

FIG. 1 is a top perspective view of one embodiment of the hooking device;

FIG. 2 is a top view of FIG. 1, the bottom view would appear as a mirror image of this top view;

FIG. 3 is a first side view of FIG. 1;

FIG. 4 is a second side view of FIG. 1;

FIG. 5 is first end view of FIG. 1;

FIG. 6 is second end view of FIG. 1;

FIG. 7 is a demonstration of the embodiment shown in FIG. 1 in use with a strap;

FIG. 8 is a top perspective view of another embodiment of the hooking device;

FIG. 9 is a top view of FIG. 8, the bottom view would appear as a mirror image of this top view;

FIG. 10 is a first side view of FIG. 8;

FIG. 11 is a second side view of FIG. 8;

FIG. 12 is first end view of FIG. 8;

FIG. 13 is second end view of FIG. 8; and,

FIG. 14 is a demonstration of the embodiment shown in FIG. 8 shown in use with a strap.

The broken line showings of the various straps in the above figures are for the purpose of showing environmental context and form no part of the claimed design.

1 Claim, 2 Drawing Sheets
